UNITED STATES PATENT OFFICE.

FRANK OGAREK, OF CARTERET, NEW JERSEY.

RAILWAY-TIE AND FASTENER.

1,162,095.

Specification of Letters Patent. Patented Nov. 30, 1915.

Application filed September 24, 1915. Serial No. 52,415.

To all whom it may concern:

Be it known that I, FRANK OGAREK, subject of the Emperor of Austria-Hungary, residing at Carteret, in the county of Middlesex and State of New Jersey, have invented certain new and useful Improvements in Rail-Ties and Fasteners, of which the following is a specification.

This invention relates to certain new and useful improvements in rail tie and fastener.

The primary object of the invention is the provision of a metallic tie for railway rails provided with a resilient readily releasable rail fastener whereby rails may be readily assembled upon or removed from the ties of the roadbed.

A further object of the device is to provide a serviceable means for removably retaining rails upon a metallic tie, the same being easy and inexpensive to manufacture, the rails being firmly maintained thereon when in position although readily released and detached therefrom whenever desired.

With these general objects in view and others that will appear as the nature of the invention is better understood, the same consists in the novel combination and arrangement of parts hereinafter more fully described, illustrated in the accompanying drawings and pointed out in the appended claims.

In the drawings forming a part of this application and in which like-designating characters refer to corresponding parts throughout the several views: Figure 1 is a side elevation of the device with the rails operatively positioned thereon, the rails being shown in vertical transverse section. Fig. 2 is a top plan view thereof. Fig. 3 is a vertical transverse sectional view through the device at a point outwardly of one of the rails. Fig. 4 is a central vertical longitudinal sectional view thereof and, Fig. 5 is an enlarged view of the rail fastener detached.

In the drawings a hollow metallic railway tie 10 is illustrated adapted to be firmly mounted upon the roadbed preferably being filled with concrete tamped therein through a side cutaway portion 11 of the tie.

The rails 12 are positioned in parallel relation upon the upper face 13 of the tie and are removably retained thereon in the manner hereinafter set forth, the attaching members being identical for each rail, although being oppositely positioned. Two

fingers 14 are carried by the tie face 13 for each rail being adapted for the ready reception of the inner base flange 15 of the rails and in a manner best illustrated in Fig. 4 of the drawing. A casing 16 rectangular in cross section is provided adjacent the ends 17 of the tie and beneath the top plate 13 thereof, two parallel slots 18 being arranged through the said plate 13 for effecting communication with the casing 16, it being also noted that the door 19 of the casing is removably retained in place by means of suitable screws 20.

A floating platform 21 is positioned within the casing 16 being mounted upon the desired number of helical springs 22 positioned between the platform 21 and the casing bottom 19. The rail fastener 23 of the form illustrated in Fig. 5 is positioned within the casing 16 and is normally seated with its base 24 flatly positioned upon the platform 21 and with perpendicularly arranged hook plates 25 carried adjacent the opposite ends of the base 24 slidably projecting through the afore-mentioned slots 18. The enlarged portions 26 of the hook plates 25 are adapted to substantially fill the slots 18, while the outer faces 27 of said hook plate portions are upwardly and inwardly inclined which together with the inner beveled edge 28 of the base 24 allows the rail fastener 23 to be forced inwardly of the slots 18 upon a depression of the supporting platform 21 and so as to assume the disconnecting position as illustrated by dotted lines in Fig. 4 of the drawing. It is to be understood that the inner projecting ends 29 of the hook plates 24 are positioned over the outer base flange 30 of the adjacent rail when desired to retain the same in place, the springs 22 being utilized to resiliently maintain the platform 21 and the rail fastener 23 in its engaged position with the rail, although the disengagement between the said members is readily effected in the manner above noted.

In assembling the elements, it will be seen that with the casing bottom 19 removed and the platform 21 mounted thereon by means of the springs 22, the rail fastener 23 may be positioned upon the platform 21 and the hook plates 25 thus readily projected through the slots 18 of the metallic tie 10 when the bottom 19 is secured in position by the screws 20. The hook plates 25 are then readily depressed out of the way for allowing the rail 12 to be inserted beneath the in-

wardly arranged fingers 14 and then the fastener 23 is released which allows the hook plates 25 to engage the forward ends 29 thereof over the outer base flange 30 of the rail. The release of the rail is also readily accomplished by forcibly depressing the rail fastener 23 which releases the hook plates from the rail flange 30.

While the form of the invention herein shown and described is what is believed to be the preferred embodiment thereof, it is nevertheless to be understood that minor changes may be made therein without departing from the spirit and scope of the invention as set forth in the appended claims.

What I claim as new is:—

1. In combination with a railway tie having parallel slots through its upper face and adjacent the end thereof, a casing beneath the said slots, a removable bottom for the said casing, a floating platform within said casing resiliently mounted upon said bottom, and a rail fastener freely positioned upon the said platform and having rail engaging means shiftably positioned through the said slots.
2. In combination with a railway tie having parallel slots through its upper face and adjacent the end thereof, a casing beneath the said slots, a removable bottom for the said casing, a floating platform within said casing resiliently mounted upon said bottom, a base seated upon the said platform, hook plates perpendicularly mounted at the

opposite ends of the said base and projecting through the said slots and having inwardly extending flange-engaging projecting ends, the said hook plates having their outer end portions beveled and the inner edge of the 40 said base being oppositely beveled.

3. In combination with a hollow metallic tie having parallel slots adjacent the end thereof, outwardly extending flange-engaging fingers carried by the said tie inwardly 45 of and in alinement with the said slots, a floating platform positioned beneath the said slots, and a rail fastener freely mounted upon the said platform and having inwardly extending hook plates shiftably projecting through the said slots.

4. In combination with a hollow metallic tie having parallel slots adjacent the end thereof, outwardly extending flange-engaging fingers carried by the said tie inwardly 55 of and in alinement with the said slots, a floating platform positioned beneath the said slots, a rail fastener freely mounted upon the said platform and having inwardly extending hook plates shiftably projecting, 60 through the said slots, and a rail positioned with its base flanges underlying the said fingers and inwardly projecting ends of the said hook plates, the said rail fastener being outwardly positioned and depressed when 65 out of engagement with the said flange.

In testimony whereof I affix my signature.

FRANK OGAREK.
